UNITED STATES PATENT OFFICE.

CHARLES D. ROSECRANS, OF HONOLULU, TERRITORY OF HAWAII.

VALVE-GRINDER.

1,299,281.

Specification of Letters Patent. Patented Apr. 1, 1919.

Application filed June 18, 1918. Serial No. 239,764.

To all whom it may concern:

Be it known that I, CHARLES DUKEWELL ROSECRANS, a citizen of the United States, and a resident of the city and county of Honolulu, Territory of Hawaii, have invented a new and Improved Valve-Grinder, of which the following is a description.

My invention relates more particularly to a valve grinder for use with the valves of internal combustion engines, insuring the gripping of the valve and facilitating its removal and manipulation for grinding. In the grinding operation it is necessary to raise the valve from the seat every few turns to change its general position on the seat and to do this by ordinary methods is attended with great inconvenience, whereas with my improved grinder this may be accomplished with facility and despatch.

Reference is to be had to the accompanying drawings forming a part of this specification, it being understood that the drawings are merely illustrative of one example of the invention.

Figure 1 is a partly sectional side elevation of a valve grinder embodying my invention, showing the same in use;

Fig. 2 is a side elevation of the valve grinder in use, the view being taken at right

angles to Fig. 1.

In carrying out my invention a shank 10 of suitable length is provided having a handle 11, both of which may be of any practical form. The valve engaging device consists of a vacuum cup 12 which in practice is of a size to be applied to a valve A. In the preferred form of my invention the vacuum cup is formed with a stem 13 on the back thereof. Said stem is received in a tubular threaded holder 14, the rear end 15 of which preferably is closed for strength and to engage the means for connecting the cup holder with the shank 10.

In the sides of the holder 14 adjacent to the closed rear end of the cap 15 of the holder, diametrical opposite holes 16 are formed, adapted to loosely receive the in-turned ends of opposite arms 17 on a yoke 18 to permit pivotal movement of the holder 14 relatively to the yoke. Said yoke 18 is received at its approximate center in a slot 20 formed in the front end of the shank 10 and is pivotally secured by a transverse pin 19 at right angles to the pivoted ends of the arms 17. Thus, the yoke 18 and the pivot

pin 19 constitute a gimbal joint between the holder 14 and the handle 11.

With a tool thus constructed the front end carrying the cup 12 is entered through the usual valve cap (not shown) and the cup applied to the top of the valve A to engage the latter and hold the same in a manner to permit of the same being lifted or turned. It is to be understood that the usual pin for retaining the valve spring (not shown) is removed before the cup 12 is applied to the valve. With the valve firmly held by the vacuum cup, the valve may be given any desired movement for grinding, the gimbal joint permitting various angular positions of the stem 10 relatively to the plane of the vacuum cup and valve. The whole operation involving the relieving of the valve from its spring pressure, and the grinding of the valve can be thus carried out quickly and with convenience.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new and desire to secure by Letters Patent:

1. A valve grinder including a vacuum cup adapted to be applied to a valve, a holder carrying said cup, a yoke having opposite arms formed with inturned ends pivotally engaging said holder at opposite sides, a handled shank having a slot therein at the front end, in which the yoke is received at its approximate center, and a pivot pin at right angles to said pivoted arms of the yoke and connecting the latter with said shank.

2. A valve grinder including a vacuum cup adapted to be applied to a valve, a stem on said cup at the back, a tubular holder having threaded engagement with said stem, a handled shank, and means loosely securing said holder at its rear end to the front end of said shank.

CHARLES D. ROSECRANS.
